UNITED STATES PATENT OFFICE.

WALTON A. EDDY, OF RANDOLPH, NEW YORK.

THILL-COUPING.

SPECIFICATION forming part of Letters Patent No. 261,144, dated July 18, 1882.

Application filed May 17, 1882. (No model.)

To all whom it may concern:

Be it known that I, WALTON A. EDDY, a citizen of the United States, residing at Randolph, in the county of Cattaraugus and State 5 of New York, have invented certain new and useful Improvements in Anti-Rattlers for Vehicles; and I do hereby declare the following to be a full, clear, and exact description of the invention, such as will enable others skilled in 10 the art to which it appertains to make and use the same.

My device relates to anti-rattling thill-couplings for vehicles; and it consists in certain details of construction and arrangement of 15 parts, as will be hereinafter more fully set forth in the specification and claim, and pointed out in the accompanying drawings, in which—

Figure 1 is a section of my device; Figs. 2, 20 3, and 4, detail views of the chucks and springs. Referring more particularly to the drawings, A represents the shaft-iron, secured to the ears of the clip H by the ordinary bolt, p. Between the curved end of the shaft-iron and the clip 25 I insert metal or rubber chucks C D. The upper one, C, has a curved or beveled front face, b, and straight back face, the front face being beveled or curved to conform to the round end of the shaft-iron. The lower chuck, D, has 30 both faces beveled, so as to permit the chuck to come up closely to the shaft-iron and sides of the clip, and at the same time leave a space between the chucks, as shown in Fig. 1. This chuck is chambered out on its under side, as 35 shown at f, Fig. 3, for the reception of a rubber washer, E, or spring K. Each chuck is perforated for the reception of a curved bolt, B,

which passes through the chuck and is curved around the end of the shaft-iron so as to allow play of the iron and allow the lower chuck to 40 come snugly into position, which would not be the case if the bolt were straight. The part of the bolt near the head is squared off so as to fit the square recess a in chuck C, and thus prevent the bolt from turning. The object of 45 the recess f in chuck D is to provide a firm seat for the washer E, or spring K, which may be used instead of washer E. When the several parts are placed in position, as shown in Fig. 1, the washer E or spring K being held 50 in the cup-shaped seat f by the metallic washer F and nut G, the shaft-iron and the several parts are held tightly and securely in place, and all rattling prevented.

Having thus described my invention, what I 55 claim, and desire to secure by Letters Patent, is—

In a thill-coupling, the combination of the shaft-iron and clip with the chucks C D, the upper one being beveled on one side and rect- 60 angular on the other side, the lower one being beveled on both sides and provided with a cup-shaped recess on its lower side for the recep- 65 tion of a rubber washer or spring, the two chucks being held and adjusted by a curved bolt, B, substantially as shown and described, and for the purpose set forth.

In testimony whereof I affix my signature in presence of two witnesses.

WALTON A. EDDY.
